DESIGN FOR A COCKTAIL SHAKER TOP OR SIMILAR ARTICLE

Finley Williams, Chicago, Ill., assignor to Fostoria Glass Company, Moundsville, W. Va., a corporation of West Virginia

Application November 17, 1934, Serial No. 54,067

Term of patent 7 years

To all whom it may concern:

Be it known that I, Finley Williams, a citizen of the United States of America, and resident of Chicago, county of Cook, and State of Illinois, have invented a new, original, and ornamental Design for a Cocktail Shaker Top or Similar Article, of which the following is a specification, reference being had to the accompanying drawing, in which—

I claim—

The ornamental design for a cocktail shaker top or similar article, substantially as shown.

FINLEY WILLIAMS.
